UNITED STATES PATENT OFFICE

KARL BAUMANN, OF URMSTON, ENGLAND, ASSIGNOR TO WESTINGHOUSE ELECTRIC
AND MANUFACTURING COMPANY, A CORPORATION OF PENNSYLVANIA.

RADIATING OR COOLING APPARATUS.

Application filed September 4, 1920. Serial No. 408,197.

To all whom it may concern:

Be it known that I, KARL BAUMANN, a citizen of the Confederation of Switzerland, and a resident of Urmston, in the county of 5 Lancaster, England, have invented a new and useful Improvement in Radiating or Cooling Apparatus, of which the following is a specification.

This invention relates to radiating or 10 cooling apparatus of the kind in which the medium to be cooled, air for example, passes over a plurality of tubes through which water is caused to circulate.

The object of my invention is to provide, 15 in conjunction with a cooler for air or other fluids in which water is circulated at a normal rate to secure a normal amount of cooling at normal capacity, a means for increasing the rate of flow of cooling fluid 20 through the cooler to increase the capacity thereof to take care of abnormal or overload requirements for the cooled air or fluid.

Fig. 1 is a diagrammatic view illustrating 25 one method of carrying out the invention and Figures 2, 3, 4, and 5 are diagrammatic views illustrating modifications of my improved device.

The efficiency with which apparatus of 30 this description operates is considerably affected by its internal condition and the velocity of flow of the water through the tubes. The capacity and efficiency of the apparatus can be considerably increased by 35 causing a greater quantity of water to pass through the tubes of the apparatus in a given time, which not only lowers the temperature of the water leaving the apparatus but also increases the efficiency of the heat 40 transmission between the water and the tubes of the apparatus.

For economical reasons it is usually desirable to provide cooling apparatus of sufficient capacity to deal only with ordinary 45 normal running conditions and to increase the capacity of the cooler when necessary by causing a greater quantity of water to traverse the tubes of the apparatus. Such latter conditions obtain for example 50 in the case of a cooling apparatus adapted to cool the ventilating air passing through a machine such, for instance, as an electric generator at such times as the machine has to carry an overload and the heat developed 55 therein is consequently increased.

According to the present invention an additional pump in the supply line, herein-after for convenience termed a booster pump, is brought into operation at those times at which it is necessary to increase 60 the quantity of water passing through the cooler.

Referring to Fig. 1, cooling water is ordinarily supplied through a pipe or passage 1 to the air cooler and the booster pump 2 is connected in what may be termed a shunt circuit, the suction pipe 3 of the pump being connected to the pipe 1 and the discharge pipe 4 of the pump being also connected to the pipe 1 but nearer to 70 the cooler than the connection of the suction pipe. A non-return valve 5 is provided in the pipe 1 between the connections of the pipes 3 and 4 with the object of ensuring that the water delivered by the pump 2 shall 75 pass to the cooling apparatus.

In Fig. 2 this arrangement of the booster pump is shown applied to a system where the ordinary supply to the cooler is effected by the circulating pump of a surface condenser. The cooler is indicated at 6 and the steam condenser at 7, the usual circulating pump 8 supplying water through the pipe 9 to the condenser, this water being discharged by the pipe 10. The circulating 80 pump 8 also causes water to pass through the pipe 1 to the cooler 6, the water after passing through the cooler being discharged through the pipe 11 into the pipe 10. The booster pump 2 with its suction and discharge pipes 3 and 4, respectively, and the non-return valve 5 are arranged as shown 85 in Fig. 1.

In a modified construction as shown in Fig. 3, the non-return valve 5 is omitted 90 and the connection between the discharge of the booster pump 2 and the water supply pipe 1 to the cooling apparatus is arranged in the form of an ejector 12 and as will be seen the discharge of water to 95 the cooling apparatus from the pipe 4 by means of the ejector action increases the quantity of water supplied through the pipe 1.

In another construction which it is not 100 necessary to illustrate, the booster pump is inserted directly in the water supply pipe or passage to the cooler. Under normal operating conditions the pump will be idle, the water passing through the pump with- 110

out its rate of flow being accelerated or its pressure increased but when the pump is operated an increased flow of water to the cooler will be caused.

5 A booster pump such as above described may advantageously be used at times for cleaning the interior of the water circulating system of the cooling apparatus. This 10 operation may be effected by increasing momentarily the water velocity of the cooling apparatus by means of the aforesaid booster pump.

In some cases in order to secure a more thorough cleaning action, sand or some 15 other suitable abrasive material, may be introduced by the booster pump into the water passing through the cooling apparatus.

As shown by way of example in Fig. 4, a sand box 13 may be connected with the inlet 20 and discharge of the booster pump, a pipe 14 being provided from the sand box to the suction pipe 3 of the pump and another pipe 15 being provided connecting the discharge pipe 4 of the pump with the upper part of 25 the sand box. Suitable valves 16 and 17 are provided in the pipes 14 and 15, respectively, so that the sand or other abrasive material can be introduced into the water circulation from the box 13 as and when required. The 30 sand box may be supplied with abrasive material from a hopper 18 provided with a valve or shut-off 19.

In another arrangement according to the invention, the booster pump may be so connected as to assist in removing leaves, dirt or other extraneous matter which may be accumulated in the cooler. For this purpose, as illustrated in Fig. 5, the pump is connected so that when in operation it causes a flow 35 of water through the cooling apparatus in the reverse direction to the normal. The normal supply of water to the cooling apparatus in the arrangement shown is similar to that of Fig. 2 but the discharge of the 40 booster pump in place of being connected to the supply 1 is connected to the discharge pipe 11 of the cooling apparatus 6 and an additional discharge pipe 20 is provided connecting what is ordinarily the inlet of 45 the cooling apparatus with the outlet pipe 10. Suitable valves 21, 22 are provided in the pipes 11 and 20 respectively. Normally, when the booster pump is not working, 50 water is supplied to the cooling apparatus through the pipe 1 and is discharged through the pipe 11 to the drain pipe 10, the valve 22 being closed and the valve 21 being opened. When, however, the pump 2 is 55 started in operation the valve 21 is shut and the valve 22 is opened and water will be 60 drawn by the pump 2 from the supply pipe and enters the cooler by the usual exit orifice and circulating through the cooler in the reverse direction leaves by the usual inlet orifice and is discharged by the pipe 20

through the valve 22 to the drain or waste pipe 10. The non-return valve 5 in the pipe 1 prevents water and leaves or other matter removed from the cooler from passing to the pump 8.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:—

1. In combination with a cooler, a supply conduit for the cooler, a circulating pump to force cooling fluid through the conduit and cooler, and a pump located in the conduit between the circulating pump and said cooler and acting only on a part of said cooling fluid to increase the velocity of flow of said cooling fluid through the cooler to increase its cooling capacity.

2. In combination with a cooler, a conduit adapted to supply cooling fluid thereto, a circulating pump causing a flow of cooling fluid through the conduit and cooler, an auxiliary pump to increase the velocity of flow of said cooling fluid through the cooler to increase its cooling capacity and a non-return means in the conduit between the intake of the auxiliary pump and the cooler.

3. In combination with a cooler and a circulating pump, a supply conduit communicating with the upper portion of said cooler, a return conduit communicating with the lower portion of said cooler, a control means in each conduit, and an auxiliary circulating pump connected to the supply conduit whereby an increased velocity is imparted to the cooling fluid through the cooler to increase its cooling capacity.

4. In combination with a cooler, a supply conduit at the top portion of the cooler, a return conduit at the bottom portion thereof, means for increasing the velocity of flow of cooling fluid through the cooler to increase its cooling capacity, and control means associated with said upper and lower conduits whereby a counter flow of high velocity cooling fluid may be circulated through the cooler.

5. The combination with a cooler having a circulating pump, of means comprising an auxiliary pump acting only on a part of the fluid discharged by the circulating pump to increase the velocity of flow of cooling fluid through the cooler.

6. In combination, a heat-exchanger of the two-fluid type, a main conduit for delivering cooling water to said heat-exchanger, a main pump supplying water to the main conduit, a shunt conduit communicating with said main conduit between the main pump and

the heat-exchanger, and an auxiliary pump in said shunt conduit.

7. In combination, a heat-exchanger of the two-fluid type, a conduit for delivering cooling water to said heat-exchanger, a main pump supplying water to the conduit, a shunt conduit having an inlet from and an outlet to the conduit between the main pump and the heat-exchanger, and an auxiliary pump in said shunt conduit.

8. In combination, a heat-exchanger of the two-fluid type, a main conduit for delivering cooling water to said heat-ex-

changer, a main pump supplying water to the main conduit, a shunt conduit having an 15 inlet from and an outlet to the main conduit between the main pump and the heat-exchanger, an auxiliary pump in said shunt conduit, and a non-return means in the main conduit between said shunt conduit inlet and 20 outlet.

In testimony whereof, I have hereunto subscribed my name this 1st day of September 1920.

KARL BAUMANN.
